CLAIM

The ornamental design for a lighted credit card tablet, as shown and described.

DESCRIPTION

FIG. 1 is a perspective view taken from the top, front and side right of a lighted credit card tablet showing our new design;

FIG. 2 is another perspective view taken from the top, front and right side thereof showing the lighted credit card tablet in a closed position;

FIG. 3 is a perspective view taken from the top, rear and left side of FIG. 2;

FIG. 4 is a perspective view taken from the bottom, rear and left side of FIG. 2;

FIG. 5 is a right side elevational view of FIG. 1, the left side being a mirror image of the right side shown; and

FIG. 6 is a front elevational view of FIG. 1.
